SCANNING DEVICE

Harry C. Nightingale, Paterson, N. J.

Application December 15, 1933, Serial No. 702,493

4 Claims. (Cl. 178—6)

My invention relates to a picture transmitting and receiving device in a simple and novel form and is accomplished by the rotation of a single cylinder with lines cut on two different angles and 5 equally spaced inside the wall of the cylinder. The angle of each line is changed from the inside to the outside to a certain degree for each line on the outside of the cylinder. These lines are on an angle across the face of the cylinder 10 to a predetermined degree. The parallel light line inside the cylinder close to the inside wall as the cylinder rotates passing the fixed parallel light, allowing a small light to pass through at the intersection from beginning to end of right 15 to left or left to right of each line at a time. I accomplish this purpose without any other mechanism or moving parts, to wit: without the use of gears, cams, mirrors, plurality of cells, plurality of cylinders, reciprocating or oscillating motions or discs or any other mechanical contrivances.

My invention is more fully described in the following specifications and drawing in which—

Figure 1 is a hollow cylinder with a cutaway sectional view showing location of masked neon light and the slots or cuts through cylinder to outer surface.

Figure 2 is end view of Figure 1.

Figure 3 is the end view of cylinder and screen whereby one may view the picture.

Figure 4 is a section of Figure #2 to illustrate the angular cut of line #1 to be projected.

Figure 5 is a section of Figure #2 to illustrate the angular cut of line #30 to be projected.

Figure 6 is a section of Figure #2 to illustrate the angular cut of line #60 to be projected.

Figure 7 is a mask or tube to confine the light source, having a fine slot to direct or allow a beam 40 of light outward; the length of which is equal to the width of the picture.

Figure 8 shows a neon lamp or light source having a small cross section of "A" of Fig. 8.

Figures 7 and 8 are shown in the cutaway section of Fig. 1 in a fixed position for operation.

Figure 9 is a section of the outer surface of Figure 1 with one of its cuts or slots passing the mask (Fig. 7) and the light source (Fig. 8) when mounted for operation within the hollow cylinder as shown in Fig. 1 cutaway section.

To understand the operation of my invention it is to be borne in mind that any transmitted television picture is composed of a number of lines per picture.

My specifications are based on a 60 line picture, which number may be increased or diminished.

In Fig. 2, the inner surface of this cylinder has 60 slots equally spaced to project the 60 lines of a picture. These slots are not equally spaced on the outer surface in order to project 60 lines of light in sequence. This arrangement of spacings enables machine to project 60 separate lines instead of one line being repeated upon itself 10 times were the slots equally spaced on inside and outside surface of cylinder.

In Fig. 2 the spacings between slots C and D are equally spaced on the inner surface, and when cut through to the outer surface of cylinder, 15 these spacings between slots F and G are not equal.

In Figure 1 a portion of the 60 slots are shown. These slots are cut at an angle of about 6 degrees to the axis of the cylinder. These slots are parallel to each other but not equally spaced on outer surface.

These slots not being parallel to center axis intersect the light beam which is directed outward from mask in Fig. 7. This mask is mounted 25 parallel to the center axis.

As any of these 60 slots pass in rotation across the fixed light beam of Figure 7, it allows only a small portion of light to pass through. That portion of light moves from right to left or left to 30 right according to the direction of rotation of the motor. This moving light forms a traveling beam which produces one projecting line of the picture.

In Figure 1 these slots are cut through in depth to the inner surface as shown in Figure 2, so that 35 the outer surface is unequally spaced but cut through to the inner surface equally spaced.

To determine the angular cuts on Fig. 2, place a cross section of the cylinder on any even surface and a fixed distance away from the center 40 lay out the cross section of screen, whose center is common to the cylinder, such as in Fig. 3. The screen is laid out in 60 equal lines. The cylinder has 60 equal spaces on its inner surface. At any of these 60 equal spaces on the inside surface of cylinder is placed upon a common center. A line is projected back from line 1 on screen to inner surface of cylinder. This determines the angular cut for line #1. The cylinder is then 45 advanced one equal division and a second line is projected to the common center as stated above. This will complete angle cut for line #2.

This procedure is carried out throughout the remaining 58 slots.

Method of operation

In rotation of hollow cylinder Fig. 1, the 60 lines or slots, 6 degrees of center to the axis cross the single light line or slot which is parallel to the axis, allowing light to pass only at the intersections. The rotation causes this intersected beam to move from end to end of each of these lines or slots and be projected on a screen.

These 60 slots or lines have an additional angle of about one degree difference each, as shown in Fig. 2 which allows the lines to be projected in sequence. This operation of the cylinder is for receiving.

For transmitting, the photoelectric cell or other similar device is substituted for the neon lamp or light source, and an image or picture is focused on the outer surface of revolving cylinder. This light passes into the cylinder through the intersections and actuates the photoelectric cell or other device, recording the modulations of light and shades, one line at a time in sequence.

Having fully described my invention, what I claim and desire to secure by Letters Patent, is:

1. A scanning system comprising a light source, a shield surrounding said source and having a single slit therein parallel to the axis of the light source, a cylindrical member surrounding the shield and having a plurality of slots cut through the surface thereof, said slots being inclined at any angle to the axis of the drum, the inner edges of the slots being parallel and equally spaced from each other, successive slots being inclined at different angles to the radial lines of a plane passes through the center of the cylinder and perpendicular to the axis thereof, means for rotating the cylinder.

2. A scanning system comprising a light source, a shield surrounding said source and having a single slit therein parallel to the axis of the light source, a cylindrical member surrounding the shield and having a plurality of slots cut through the surface thereof, said slots being inclined at

an angle to the axis of the drum, the inner edges of the slots being parallel and equally spaced from each other, successive slots being inclined at different angles to the radial lines of a plane passed through the center of the cylinder and perpendicular to the axis thereof, means for rotating the cylinder, thereby causing the intersection of the shield slit and a slot to form a moving light spot, and means for modulating the light source.

3. A scanning system comprising a light source, a shield surrounding said source and having a single slit therein not parallel to the axis of the light source, a cylindrical member surrounding the shield and having a plurality of slots cut through the surface thereof, said slots being inclined at an angle to the axis of the drum, the inner edges of the slots being parallel and equally spaced from each other, successive slots being inclined at different angles to the radial lines of a plane passed through the center of the cylinder and perpendicular to the axis thereof, means for rotating the cylinder, thereby causing the intersection of the shield slit and a slot to form a moving light spot, and means for modulating the light source.

4. A scanning system comprising a light sensitive device, a shield surrounding said light sensitive device and having a single slit therein parallel to the axis of the light sensitive device, a cylindrical member surrounding the shield and having a plurality of slots cut through the surface thereof, said slots being inclined at an angle to the axis of the drum, the inner edges of the slots being parallel and equally spaced from each other, successive slots being inclined at different angles to the radial lines of a plane passed through the center of the cylinder and perpendicular to the axis thereof, means for rotating the cylinder and thereby causing successive points of light to fall on the photo-cell.

HARRY C. NIGHTINGALE.
